CLAIM

I claim the ornamental design for the adhesive pad for retail sensor, as shown and described.

DESCRIPTION

FIG. 1 is a perspective view of the adhesive pad for retail sensor;

FIG. 2 is a top view thereof;

FIG. 3 is a front view thereof;

FIG. 4 is a side view thereof;

FIG. 5 is a bottom view thereof;

FIG. 6 is a side view thereof showing the side opposite that shown in FIG. 4;

FIG. 7 is a back view thereof;

FIG. 8 is a perspective view showing the design in an alternate position;

FIG. 9 is a second perspective view showing the design in an alternate position; and,

FIG. 10 is an enlarged side view taken along the bottom corner of the design as seen in FIG. 4.
